(57) **CLAIM**

The ornamental design for a weed guard for a fishing lure body, as shown and described.

DESCRIPTION

FIG. 1 is a right side elevational view of the weed guard projecting upwardly from a rounded mounting portion on the fishing lure body to project above and to the sides of the barb of the hook member extending outwardly from the rounded tail of the body portion, the fishing lure body and hook member being shown in broken lines and not forming a part of this design;

FIG. 2 is a bottom plan view thereof;

FIG. 3 is a left side elevational view thereof;

FIG. 4 is a top plan view thereof;

FIG. 5 is a front elevational view thereof;

FIG. 6 is a rear elevational view thereof;

FIG. 7 is a front perspective view of the weed guard;

FIG. 8 is a front elevational view of an alternative embodiment of the weed guard with the central tine of the weed guard being shown in phantom and not forming a part of the invention; and,

FIG. 9 is a rear elevational view of the weed guard embodiment shown in FIG. 8.
